UNITED STATES PATENT OFFICE.

HERBERT W. DAY, OF WOLLASTON, MASSACHUSETTS, ASSIGNOR TO SPRAY ENGINEERING COMPANY, OF BOSTON, MASSACHUSETTS, A CORPORATION OF MASSACHUSETTS.

APPARATUS FOR APPLYING COATING.

Application filed March 1, 1922. Serial No. 540,170.

To all whom it may concern:

Be it known that I, HERBERT W. DAY, a citizen of the United States, and a resident of Wollaston, in the county of Norfolk 5 and State of Massachusetts, have invented an Improvement in Apparatus for Applying Coating, of which the following description, in connection with the accompanying drawings, is a specification, like 10 characters on the drawings representing like parts.

This invention relates to apparatus for applying coating to surfaces.

The coating, if a liquid, may be a paint, 15 japan, varnish or any other suitable coating medium, or it may, if desired, be a solid in powdered form, and the material or surface to which it is to be applied may be of any character, such, for example, as 20 wood, metal or other material.

Referring more particularly to the drawing, wherein I have represented a single embodiment of my invention,—

Fig. 1 is a vertical longitudinal section 25 of a tool constructed in accordance with my invention;

Fig. 2 is a vertical longitudinal section of the discharge end of the tool, but representing the parts positioned to cut off the 30 discharge of the motive agent supplementally; and

Fig. 3 is an end elevation of a tool looking toward the right in Fig. 1.

The tool or appliance may be of any 35 suitable material but is preferably metallic and may be of the general form shown in my Patent No. 1,172,233, dated February 15, 1916, or of any other suitable form of construction. The body 1 is, however, preferably provided with a handle or extension 2 integral therewith and provided with a guard 3 inclosing the free end of the valve operating lever 4 pivoted at 5 upon the body 1. In the disclosed form of the invention, the said operating lever 4 is of general trigger form, but such construction may be widely varied within the scope and purpose of the invention.

The handle 2 is provided with a passage 6 50 for the paint or other suitable coating liquid or powder, which may be supplied through gravity or under suitable pressure if desired and also with a passage 7 for the air or other suitable fluid under pressure.

In the form of tool herein shown, I have 55 represented the passages 6, 7 as pipes suitably secured in the body 1 and as communicating at their inner ends with passages 8, 9 cored or otherwise suitably provided in the body 1. Controlling the paint supply passage 8 is a valve which may be of any suitable form, but which is herein represented as an axially movable piston or plunger 10 positioned within a valve casing 11 and having a stem 12 extending 60 through the valve casing into contact with the operating lever 4, as clearly shown in Fig. 1. The valve here shown as a piston or plunger is normally held seated by a coiled spring 13 surrounding the stem 12 70 and seated in a recess 14 in a cap 15 threaded at 16 into the body 1 similarly threaded at 17.

The passage 9 for the air is controlled by a similar valve indicated generally at 75 18 in Fig. 2, the spindle 19 thereof contacting with the valve operating lever 4 which is shaped so as to engage both valves in a manner herein unnecessary more fully to illustrate.

The body 1 is cored to provide a longitudinal passage 20 which is internally threaded at 21, 22 for the reception respectively of a tubular member 23 threaded at 24 and a needle valve 25 threaded at 26. 80 The tubular member 23 at its forward end is preferably suitably formed to permit the passage of the coating material issuing from the valve chamber 10 into the passage 27 and thence into the circumferential space 90 28. For this purpose the forward end of the tubular member 20 is preferably squared. Thus the coating material, when the valve 10 is opened, is permitted to flow through the passage 6, the valve casing 11, the passages 27, 28, and thence past the squared formation. Upon the forward end of the tubular member 20 is threaded or otherwise positioned a cap 30, which may be similar, if desired, to the corresponding 95 member in my Patent No. 1,172,233. The needle valve 25 is seated at its outer end of the cap 30 as indicated in Fig. 1, and the forward end of the said needle valve is guided and positioned by any suitable 100 means, as, for example, by a coiled wire 31 encircling the head of the valve and maintaining it in a central position when

the valve is unseated. The rear end of the valve 25 may be provided with a suitable lock nut 32.

The air passage 9 is in communication 5 with a passage 33 indicated in dotted lines in Fig. 1, which is itself in communication with the valve chamber containing the valve 18 and extending from such valve chamber is an air passage 34 indicated in dotted lines 10 in Fig. 1 and communicating with a passage 35 forming an enlargement of the passage 36 of the tubular member 20. When the valve 18 is opened, the air flows through the passage 33 past the valve 18 through the 15 passages 34, 35, and into the passage 36 governed or controlled by the needle valve 25.

Upon the outer end of the body 1 is threaded or otherwise suitably secured a preferably cap-like member 37 herein shown 20 as having a concaved or curved inner surface 38 and a small central opening 39 in line with the axis of the needle valve 25. The length of the threaded portion 40 of the cap like member 37 is sufficient to permit adjustment of the member 37 so as to provide for the effective formation of a film and the variation of the thickness thereof, as described in my Patent No. 1,172,233. Such film is constantly formed and maintained by capillary action between the surface 38 and the outer surface 41 of the inner cap 30 which are brought close enough together to insure such action. The air entering through the passage 36 breaks through 30 the film at the central portion of the cap and discharges the same upon the work in very fine globules. Said film is constantly broken by the air or other fluid but is constantly restored through the action of capillarity. Hence the coating material may be merely under suction due to capillary action. The maintenance of the supply of coating material is not dependent upon the presence of the air current which is used 40 merely to break the film and discharge the globules. I effect through the described construction a very fine division of the coating material as set forth in my Patent No. 1,172,233.

50 The construction of parts thus far described effects the formation of a mass of spray of general conical form issuing through the orifice 39, but generally circular in cross section. This result is effected by 55 the disruption of the film formed between the cap like members 30, 37 through the agency of the air or other suitable fluid in the manner already described.

I am aware that it has been proposed to 60 modify the character of the spray issuing from a tool or appliance for applying coating by means of supplemental jets of air directed upon the discharged spray, as shown, for example, in the patent to Burdick, No. 649,430, dated May 15, 1900. In accordance

with this patent, the shape of the spray discharge is changed from a circular form into that of a thin sheet through the use of supplemental air jets directed upon the spray issuing from the discharge end of the tool or 70 like appliance.

As fully set forth in my Patent No. 1,321,014, I therein provide for discharging supplemental air jets upon the discharged film of paint or other coating material and 75 in such a manner as to change or transform the issuing spray from a conical formation circular in cross section into a sheet. In said patent, I disclose means and a process whereby a mass of spray as discharged may 80 be given any form in cross section between that of a relatively thin sheet and a cone or mass circular in cross section.

In accordance with the present invention, I provide means whereby the issuing spray 85 may be permitted to retain its shape defined as circular in cross section or whereby said issuing spray may be given the form of a relatively thin sheet in any position throughout the circumferential extent of the 90 tool or apparatus.

I provide a generally cylindrical member 42 having any suitable number of (and preferably two) tubular extensions 43, 44 preferably diametrically opposed to each 95 other and terminating in discharge passages 45, 46 desirably inclined toward each other and clearly represented in Fig. 1.

The two or other number of supplemental air passages 43, 44 are in communication at 100 their inner ends through ports or passages 47, 48 with a completely annular passage or groove 49 formed upon the outer surface of the forward end of the body 1, as indicated in Fig. 1. Said annular passage or 105 groove is in constant communication with said ports or passages 47, 48, throughout the entire circumferential extent of rotation of the cylindrical member 42 until said member 42 has been turned a sufficient number of 110 times upon the body 1 to withdraw the said ports 47, 48 out of alignment or communication with the said annular groove or passage 49, as indicated in Fig. 2. This result is accomplished in any suitable manner but 115 preferably by providing the body 1 with an extended threaded surface 50 and the inner surface of the cylindrical member 42 with a similar thread 51. The construction is such that said member 42 may be rotated 120 sufficiently to be moved from the position indicated in Fig. 1 into the position indicated in Fig. 2, and thereby cut off communication with the annular passage 49. So long, however, as the passages 47, 48 are in 125 communication with the annular groove or passage 49, the jet orifices 45, 46 may be placed in any position throughout an entire circle of movement, and hence the thin sheet or line of coating material may lie in any 130

plane or position throughout an entire circumference.

The passages 47, 48 are of such size as to permit rotative movement of the member 2 throughout a complete circle without interfering at all or to any substantial extent with the discharge of the motive agent supplementally through the passages 43, 44. The annular passage or groove 49 and hence 10 the passages 43, 44 are in communication with the longitudinally extending passage 52 and the communicating passage 53 of the body 1, such passage 53 being in communication with the main air passage 35 through 15 a small port 54. Said port 54 is not controlled by a valve, as in my said Patents No. 1,321,014 and No. 1,368,612, since in order to interrupt the communication between the main air passage 35 and the supplemental air passages 43, 44, I depend wholly upon a continued turning movement of the cylindrical member 42, sufficient to move it into or substantially into the position shown in Fig. 2.

25 It will be evident that the annular passage or groove 49 may if desired be formed in the inner surface of the member 42 and that other changes may be made within the scope and purpose of the invention. In my 30 Patent No. 1,368,612, I have shown a cylindrical member 42 adapted to be turned upon the body for the purpose of changing the plane of discharge of the supplemental jets, this being effected through a turning movement 35 permitted by a threaded connection, thereby incidentally involving a slight longitudinal movement, not for the purpose of cutting off the supplemental air supply, as that is effected by the valve 55, and expressly counteracted by the enlargement of 40 the passages 47, 48, 49.

In the present invention I provide for adjustment in both directions longitudinally and provide a relatively prolonged threaded surface both in advance and in the rear of the annular passage 49. It is evident that if the adjustment were only in a forward direction, then unless the rear end of the member 42 were very thick, adjustment sufficient to cut off the supplemental air supply might leave the annular passage 49 wholly unclosed in the rear of said member 42. Further, the present construction gives a more prolonged engagement between the body and the member 42, and prevents possibility of leakage. It also permits more extensive variation of the point or place at which the supplemental jets impinge upon the main jet.

45 My invention in its broadest application is not limited to the formation of a film of the coating material, since such coating material may be positioned with respect to the discharging motive fluid in any suitable manner. Preferably, however, I provide for

forming, breaking through and discharging the film.

Having thus described one illustrative embodiment of my invention, I desire it to be understood that although specific terms are employed, they are used in a generic and descriptive sense and not for purposes of limitation, the scope of the invention being set forth in the following claims.

Claims—

1. Means for applying coating comprising a body having means for supplying coating material, and having means to subject the same to the action of a motive agent, thereby effecting the discharge of the coating material, and means mounted for complete circumferential movement about said body to discharge a motive agent supplementally upon the discharged coating material at any angle, said means to discharge the motive agent being longitudinally adjustable in both directions upon said body and thus constituting the sole means whereby such supplemental discharge is permitted or is wholly cut off without affecting the main air supply. 90

2. A tool for applying coating comprising a body having passages for coating material and for a motive fluid under pressure and a member supported upon said body and having one or more supplemental motive-agent discharge passages adapted to communicate with the motive agent supply passage, said member being longitudinally adjustable upon the body in both directions so as wholly to cut off the supplemental supply 100 of the motive agent or to permit such supply and constituting the sole means to control the supplemental supply without affecting the main air supply.

3. A tool for applying coating comprising a body having passages for coating material and for a motive fluid under pressure and a member supported upon said body and having one or more supplemental motive-agent discharge passages adapted to communicate with the motive agent supply passage in said body, the said member having ports corresponding in size to the motive agent supply passage and having a threaded engagement with the body permitting it 110 to be moved thereon for the purpose of wholly cutting off without leakage all communication with the motive agent supply passage and constituting the sole means to control the supplemental supply without affecting the main air supply. 115

4. A tool for applying coating comprising a body having passages for coating material and for a motive agent under pressure, a member 42 supported upon said body and having passages 47, 48, the body having an annular passage 49 adapted to communicate in all positions of circumferential adjustment with the passages 47, 48 said passages 47, 48 and 49 corresponding in size, 125 130

said member 42 being capable of longitudinal adjustment, for the purpose of wholly cutting off without leakage all communication between the annular passage 49 and the passages 47, 48 and constituting the sole means to control the supplemental supply without affecting the main air supply.

5. A tool for applying coating comprising a body having passages for coating material 10 and for a motive agent under pressure, said body having a supplemental air passage terminating in an annular passage, the surface of said body at opposite sides of said annular passage being threaded for a relatively extensive area, a member 42 threaded upon said body and having passages 47, 48 adapted to communicate with said annular passage in all positions of circumferential adjustment, said member 42 being capable 20 of longitudinal adjustment in both directions upon said extensive threaded areas so as wholly to cut off communication between the annular passage and said passages 47, 48.

6. A tool for applying coating comprising 25 a body having passages for coating material and for a motive agent under pressure, said body having a valveless supplemental air passage 53, 52 terminating in an annular passage 49 at the surface of said body, the latter being extensively threaded in the rear 30 of and in advance of said annular passage, and a member 42 supported upon said body and having passages 47, 48 adapted to com-

municate in all positions of circumferential adjustment with said annular passage, said member 42 being capable of longitudinal adjustment in both directions upon said extensively threaded area so as to cut off communication between the annular passage and said passages 47, 48.

7. A tool for applying coating comprising a body having passages for coating material and for a motive agent under pressure, said body having a supplemental air passage terminating in an annular passage, a supplemental jet member mounted upon said body and having passages for supplemental air adapted to be placed in communication with said annular passage, said supplemental jet member having circumferential movement 50 about said body, its passages for supplemental air being adapted to communicate with the annular passage in all positions of circumferential adjustment, said supplemental jet member being movable longitudinally of 55 said body in both directions sufficiently to cut off the supplemental air, without leakage when moved in both directions longitudinally, said supplemental jet member constituting the sole means for cutting off the supplemental discharge without affecting the main air supply.

In testimony whereof, I have signed my name to this specification.

HERBERT W. DAY.
